UNITED STATES PATENT OFFICE.

EMANUEL MYETTE, OF PROVIDENCE, RHODE ISLAND.

MACHINE FOR REELING OR SPOOLING WIRE AND THE LIKE.

1,233,106.

Specification of Letters Patent. Patented July 10, 1917.

Application filed January 18, 1917. Serial No. 143,101.

To all whom it may concern:

Be it known that I, EMANUEL MYETTE, a citizen of the United States, residing at Providence, in the county of Providence and State of Rhode Island, have invented a new and useful Improvement in Machines for Reeling or Spooling Wire and the like, of which the following is a specification.

This invention relates to certain new and useful improvements in machines for reeling or spooling wire and the like, and the primary object thereof is to provide a machine of this character which embodies improved means for effecting automatic slowing up of the movement of the laying means upon increase of the diameter of the reel or spool upon which the wire is being laid.

Further, the invention aims to provide means for the purpose above mentioned, which is certain and positive in its action, and which is devoid of parts subject to becoming easily rendered inoperative or inefficient in action.

Still further, the invention aims to provide means which is compactly organized and of simple economical structure to attain the purpose mentioned.

Further and other objects will be later herein set forth and manifested in the course 30 of the following description.

In the drawings—

Figure 1 is a side elevation of the invention.

Fig. 2 is a top plan view, partly in section.

Fig. 3 is a section on line 3—3 of Fig. 2.

Fig. 4 is a rear end elevation of the worm drive, and

Fig. 5 is a detail view of the worm and nut.

In proceeding in accordance with the present invention there is employed a suitable base 1 which at one end has vertical standards 2 revolubly supporting a spool or bobbin 3 upon which latter wire W from a suitable drum D is laid. A finger follower 4 which rides on the last coil of wire being wound is pivoted at 5 to an arm 6 forming part of the worm nut which latter is supported on a worm shaft 7. The follower 4 has a roller 8 mounted on its rear end. The

shaft 7 is journaled in uprights 9 and has a gear 10 on one end thereof, which gear meshes with a gear 11 journaled on one of the standards 9, and gear 11 in turn intermeshes with a gear 12 mounted on a stub 55 shaft 13. The stub shaft 13 has a pulley 14 thereon over which is trained an endless belt 15, the latter engaging over a pulley 16 mounted on a shaft 17, the latter being journaled in suitable uprights 18 borne by the 60 base 1. Mounted on the shaft 17 is a cone pulley 19 which drives a cone pulley 20, the latter being reversely related to the cone pulley 19, through the medium of an endless belt 21. Cone pulley 20 is mounted on a 65 shaft 22 which latter has a pulley 23 on its outer end over which is trained an endless belt 24, the latter engaging a pulley 25 mounted on the bobbin shaft 26. A second pulley 27 is mounted on the bobbin shaft 26 70 and derives power from the belt 28 trained thereover, which latter in turn derives power from any suitable source.

Mounted in suitable guides 30 formed in the standards 9 is a sliding weighted frame 75 31 which frame is formed with a longitudinal opening 32 through which the roller 8 of the finger follower 4 loosely projects, and connected to the lower end of the frame is one end of a chain or cord 33 which 80 is trained over pulleys 34, 35 and 36 and connected at its opposite end to a suitable belt shipper 37. This belt shipper is shown as embodying a member slotted to receive the belt 21 so as to ship the belt either to 85 the right or left by engagement with the opposite sides of the belt 21, as is manifest. The opposite end of the belt shipper is connected to one end of a cord or chain 38 which latter is trained over a pulley 39 and 90 is tensioned in any suitable manner, as for instance by the weight 40.

Arranged in overlying relation to the worm shaft 7 is a guide formed of two spaced horizontal members 41 which are 95 spaced apart and preferably set on edge so as to engage the wire W and support the same, and received in the space between the guides 41 are a pair of vertically extending guide fingers 42, which latter are mounted 100

on a nut 43 which receives the worm 7. The nut 43 supports arm 6 and is formed with a suitable dog 53 engaging with the worm so that after traversing the length of the latter the nut and therewith guide fingers 42 will be caused to move in the opposite direction so as to thus successively lay the wire on the bobbin 3. The worm as shown has right and left hand threads connected at each end by the curved grooves 60. The operation is as follows:

Power is applied to the pulley 27 through belt 28 which drives the bobbin shaft 26 and therewith the bobbin 3 and at the same time drives the belt 24. The belt 24 drives the pulley 23 of the shaft 22, and the latter by virtue of carrying the lower cone 20 and through the medium of the belt 21 drives the upper cone 19 and therewith shaft 17, and since shaft 17 has a pulley 16 thereon, the latter drives the belt 15 and pulley 14 engaged with belt 15. The pulley 14 being mounted on the stub shaft 13, the latter carrying the gear 12, it will be seen that since the gear 12 meshes with the gear 11 and the latter meshes with the gear 10 of worm shaft 7, the worm shaft is consequently rotated and the latter, through the nut 43 effects movement of the follower finger 4. When now the layers on the bobbin 3 increase and the diameter of the latter is thus accordingly increased it will be seen that the follower finger 4 will be moved outwardly by each succeeding layer of wire causing the roller 8 of the finger to be raised and since the weight frame 31 rests on roller 8, the frame will be raised pulling on the chain 33, so as to move the shipper 37 and therethrough belt 21, so as to control the speed of the worm shaft 7 accordingly so as to effect a slower motion of the worm shaft as the diameter of the spool or bobbin 3 increases. When the dog 53 of nut 43 reaches the ends of the worm 7 it will be seen that this dog will ride from the left hand thread into the right hand thread by reason of the curved grooves 60 which act to effect this transference of the dog, consequently the dog will be reciprocated along the length of the worm 7 so as to cause corresponding movement of the follower finger 4, and therewith movement of the fingers 42, which latter effect proper laying of the wire.

Having thus described my invention, what I claim as new and desire to secure by Letters Patent is—

1. In a machine of the type set forth, a bobbin shaft, reciprocating means to lay the wire on the bobbin, a follower finger engageable with the wire on the bobbin and pivoted to the laying means, guides, a weighted frame slidable vertically in the guides and having a longitudinal opening through which the inner or rear end of the

follower finger slidably projects so as to support the frame, upper and lower reversed cones, a belt connecting said cones, variable speed means to drive the laying means from one of the cones, means to drive the bobbin shaft and the other cone, a shipper for the belt, means to tension the shipper, and means connecting the weighted frame and the shipper for effecting movement of the shipper by the movements of the frame.

2. In combination with a bobbin shaft, and a bobbin thereon to receive wire or the like, a slidable weighted frame having an elongated opening, means to drive the shaft, means to lay the wire on the bobbin, variable speed control means to drive the laying means, a follower engageable with the wire and having a part projecting through and slidable in said opening of the frame and supporting the latter, variable means to drive the laying means, and means controlled by the vertical movements of the weighted frame to vary the movement of the drive of the laying means.

3. In combination with a bobbin and a drive therefor, laying means, variable speed control means to drive the laying means, weighted means to control the variable speed control driving means, and pivoted means bearing on the material and associated with the laying means to control the weighted means by the increase of the material wound on the bobbin.

4. In combination with a bobbin drive, and reciprocating laying means, pivoted means engageable with the material wound on the bobbin and movable by the increase of diameter of the material, a variable speed drive for the laying means, and means controlled by the movements of the pivoted means to effect control of the variable speed drive.

5. In combination with a bobbin drive, and laying means, a variable speed drive for the laying means, tensioned means for varying the speed drive of said means, weighted means connected to the tensioned means, and a pivoted follower engageable with the material wound on the bobbin and with the weighted means to move the latter against the tension of the tensioning means.

6. In combination with a bobbin drive, and laying means, a variable speed drive for the laying means, including a belt shipper, means to tension the shipper, a slidable weighted frame connected to the shipper to move the same against the tension of said tensioning means, said weighted frame having a longitudinal slot, and means controlled by the increase in diameter of the material wound on the bobbin and slidable through said slot of the frame to raise the latter.

7. In combination with a bobbin drive,

laying means, a variable speed drive therefor, weighted means to control the variable speed drive, and means slidably associated with the weighted means to raise the latter and being controlled by the diameter of the material wound on the bobbin.

In testimony whereof I have signed my

name to this specification in the presence of two subscribing witnesses.

EMANUEL MYETTE.
